United States Patent Office

Des. 225,684
Patented Dec. 26, 1972

225,684

GEAR HOUSING

David B. Bogan, Los Angeles, Calif., assignor to David B. Bogan Corporation, Sherman Oaks, Calif.

Filed Nov. 30, 1970, Ser. No. 26,229

Term of patent 14 years

Int. Cl. D15—99

U.S. Cl. D55—1

FIG. 1 is a perspective view of the gear housing showing my new design;

FIG. 2 is a perspective view of the gear housing showing the opposite side from the side shown in FIG. 1;

FIG. 3 is an end elevational view thereof;

FIG. 4 is an end elevational view of the other end thereof;

FIG. 5 is a top plan view thereof;

FIG. 6 is an enlarged side elevational view thereof; and

FIG. 7 is an enlarged side elevational view thereof showing the opposite side from the side shown in FIG. 6.

I claim:

The ornamental design for a gear housing, substantially as shown and described.
